Patented July 2, 1918.

Charles W. Link, ^{INVENTOR}

Edmund G. Strause, ^{BY} ATTORNEY

UNITED STATES PATENT OFFICE.

CHARLES W. LINK, OF LOS ANGELES, CALIFORNIA.

DESIGN FOR AN AUTOMOBILE-TOP.

52,142.

Specification for Design.

Patented July 2, 1918.

Application filed February 7, 1918. Serial No. 215,913. Term of patent 3½ years.

To all whom it may concern:

Be it known that I, CHARLES W. LINK, a citizen of the United States, residing at Los Angeles, in the county of Los Angeles and State of California, have invented a new, original, and ornamental Design for Automobile-Tops, of which the following is a specification, reference being had to the accompanying drawing, forming part thereof.

Figure 1, is a perspective view of my new automobile top looking from the rear.

Fig. 2, is a perspective view of my new automobile top looking from the front.

I claim:

The ornamental design for an automobile top, as shown.

CHAS. W. LINK.

Witnesses:

JEANETTE CHILDS,
WALTER DICK.
